UNITED STATES PATENT OFFICE.

MILES L. LEOB, OF CLEVELAND, OHIO.

DETACHABLE TOOTH-FACING FOR BRIDGWORK OR GOLD PLATES.

SPECIFICATION forming part of Letters Patent No. 777,521, dated December 13, 1904.

Application filed February 23, 1904. Serial No. 194,971. (No model.)

To all whom it may concern:

Be it known that I, MILES L. LEOB, a citizen of the United States, and a resident of Cleveland, county of Cuyahoga, State of Ohio, have invented certain new and useful Improvements in Detachable Tooth-Facings for Bridgework or Gold Plates, of which I hereby declare the following to be a full, clear, and exact description, such as will enable others skilled in the art to which it appertains to make and use the same.

The general objects of my invention are to provide means whereby a porcelain tooth-facing can be readily attached and detached from the metal backing and to provide a metal rim for the incisive edge of the tooth, so that the porcelain will be protected and uninjured by the acts of mastication.

The invention consists in a porcelain tooth or facing of porcelain in which a dovetailed groove has been cut, and a corresponding dovetail projection is formed upon the inside of the metal back, adapted to engage with the dovetailed groove in the porcelain and upon which the porcelain facing can only be fitted in one direction—that is, by applying the incisive edge of the first to the dovetailed projection.

The invention also consists in the turned edge of the backing upon which the incisive edge of the facing rests.

The invention also consists in the details of construction and combination and arrangement of minor parts, as hereinafter described, shown in the accompanying drawings, and specifically pointed out in the claim.

In the accompanying drawings, Figure 1 is a perspective view of a bridge of six teeth, showing the metal back, where two of the porcelain facings have been omitted. Fig. 2 is a longitudinal central section through a metal socket, showing the manner of attaching the porcelain facing and for protecting its incisive edge. Fig. 3 is a similar section through one of the central plates between the sockets. Fig. 4 is a central transverse section through the same. Fig. 5 is a perspective view of one of the central backing-plates before it is inserted in the bridge; and Fig. 6 is a perspective view of the inner side of a

tooth-facing, showing the dovetail groove cast therein. Fig. 7 shows the adaptation to a molar tooth.

In the views, 1 is the porcelain facing, which is beveled away at each end, the upper edge at 2 to afford room for the gum and the lower edge at 3 so that the metal backing can approach the incisive edge and protect the tooth from strain.

4 is a dovetail groove longitudinally cast in the back of the facing and extending through the bevel at the lower edge, but not extending through the upper or gingival bevel, for the reason that in this manner the saliva will be prevented from gaining access to the dovetail groove and the cement, by means of which the parts are secured together. The wall at 5 therefore serves to protect the groove.

6 is the gold or other metal backing, upon the inner face of which is secured or cast the projecting dovetail 7, which is inserted in the corresponding groove in the facing. This projection is provided with the shoulder 8 at its upper end, which strikes against the wall at 5 and limits its movement. The lower edge 75 of the metal backing is turned outwardly at 9 to follow the bend of the edge of the porcelain, and the edge of the backing is bent outwardly under the edge of the tooth at 10, thus supporting and protecting it.

It will readily be seen that the facing can only be placed in position from the upper edge of the backing and when cement or gutta-percha is applied the facing becomes rigidly attached to the backing without danger of subsequently loosening. The gutta-percha can readily be removed to separate the parts by heating.

The construction is exceedingly effective and simple, cheap in initial cost, and permits of a heavy metal edge protecting the incisive edge of the facing.

In Fig. 7 the adaptation of the invention to a molar tooth is shown. Here 11 is the porcelain for the groove and 5 the limiting-wall. 95 Since, however, the porcelain needs no protection on its lower edge, the metal backing is not continued far beyond the groove, and the protection for the groove to prevent moisture from entering it can be arranged by cov- 100

ering the open end of the groove with some part of the metal backing.

Having described my invention, what I claim as new, and desire to secure by Letters 5 Patent, is—

An artificial tooth comprising, in combination, a metal backing, consisting of a plate extending to the gingival bevel of the tooth, and beveled at the incisive end, a dovetailed projection upon said plate extending against the beveled portion of said plate, a porcelain facing beveled outwardly at both ends, and a

dovetailed slot in said facing, extending longitudinally of the facing through the bevel at the incisive end, to within a short distance 15 of the bevel at the gingival end of the facing, substantially as described.

In testimony whereof I hereby set my hand this 10th day of February, 1904.

MILES L. LEOB.
